DESIGN FOR A HINGE

William D. Ferris, Sterling, Ill., assignor to Frantz
Manufacturing Co., Sterling, Ill., a corporation
of Illinois

Application January 24, 1934, Serial No. 50,493

Term of patent 3½ years

To all whom it may concern:

Be it known that I, WILLIAM D. FERRIS, a citizen of the United States and resident of Sterling, in the county of Whiteside and State of Illinois, have invented a new, original, and ornamental Design for a Hinge, of which the following is a specification, reference being had to the accompanying drawing forming a part thereof:

Fig. 1 is a front elevation of a hinge showing my new design.

Fig. 2 is a view looking down on the hinge shown in Fig. 1 of the drawing.

The device of my design comprises the several elements shown in solid black lines in the drawing, combined with the leaf shown in dotted lines. The dominant features of the design are shown in the solid black lines.

I claim:

The ornamental design for a hinge, as shown and described.

WILLIAM D. FERRIS.
